STOCKING

Joseph Largman, Philadelphia, Pa.

Application April 13, 1943, Serial No. 482,841

2 Claims. (Cl. 66—173)

This invention relates to full-fashioned hosiery and more particularly to improvements in the design and construction of the upper or welt portion of the stocking.

Heretofore and prior to the present invention, it has been the general practice in the manufacture of full-fashioned hosiery to knit the welt fabric to a sufficient length to form the conventional double top or welt, following which the welt is "turned" and interknitted into the leg or body fabric of the stocking. In accordance with conventional practice, the welt fabric is knitted of a heavier yarn than that employed for knitting the body fabric with the result that in all such stockings, the sheer or non-reinforced leg portion of the stocking extends to and terminates abruptly at the bottom edge of the doubled welt. Unless this doubled welt is formed of considerable depth, which in most cases is quite undesirable, the natural tendency for the wearer of the stocking is to secure the hose supporter clasp in the non-reinforced leg portion of the stocking at a point below the welt. This results in a severe strain and pull on the body fabric with consequent weakening of the body yarn and the creation of "runs" in the leg fabric.

It is among the objects of the present invention to overcome this difficulty by providing a stocking having a single ply "after-welt" formed immediately below the conventional doubled top or welt of the stocking, said after-welt being so knitted and reinforced as to provide it with sufficient strength to enable hose supporters to be anchored therein.

A further object of the invention is to provide a full-fashioned stocking with a single ply "after-welt" which is interposed between the conventional doubled top or welt and the non-reinforced leg body of the stocking and which is knitted in such manner as to create an improved balance between the reinforced welt and non-reinforced leg portions of the stocking, thus materially enhancing the general appearance of the stocking in the region of its welt.

A still further object of the present invention is to provide a stocking with an after-welt which is commonly knitted of the non-reinforced yarn forming the leg fabric and of the heavier or reinforced yarn forming the welt fabric, in consequence of which there is provided between the doubled welt and the leg body of the stocking a reinforced region of substantial depth which serves to blend the more or less sheer leg fabric with the heavier welt fabric to thereby not only improve the appearance of the stocking as a

whole, but also provide for increased strength and additional gartering area in the region immediately below the doubled welt.

Other objects and advantages of the invention will be apparent more fully hereinafter, it being understood that the invention consists substantially in the combination, construction, location and relative arrangement of the several parts of the stocking, all as will appear more fully herein-after, as shown in the accompanying illustrative drawing, and as finally pointed out in the appended claims.

In the said drawing, which is not intended to be restrictive, but merely illustrative of a preferred form of the invention:

Figure 1 is a perspective view of a stocking constructed in accordance with and embodying the principles of the present invention;

Figure 2 is a sectional view taken on the line 20 3—3 of Figure 1; and

Figure 3 is a diagram of the knitted loop formation of the after-welt of the present invention.

Referring now more particularly to the drawing, it will be observed that the stocking 10 is provided with the usual leg and foot portions 11 and 12 respectively and with a conventional doubled welt portion 13. Intervening the welt portion 13 and the leg portion 11 is the after-welt portion 14 and it is in relation to this latter portion of the stocking that the present invention is particularly directed.

In fabricating the stocking of the present invention, the welt fabric is knitted of a heavier thread than is the web of the leg portion 11, the denier ratio of the yarns respectively constituting the main welt fabric and the sheer leg fabric being preferably on the order of 75 to 50, although this ratio may be varied as desired without departing from the principles of the present invention. In accordance with conventional practice, the main welt fabric, which is preferably knitted of yarn having a denier of 75 or more, is doubled upon itself in such manner as to provide the top welt 13 of doubled thickness.

45 After the welt has been turned, knitting of the stocking fabric is continued to produce the after-welt portion 14 and the leg portion 11 in continuation thereof, the after-welt being knitted of the two yarns which are respectively employed in the knitting of the welt portion 13 and the leg portion 11 of the stocking. The leg yarn, being of a substantially less denier than the welt yarn, preferably about 50, is reinforced by the welt yarn to thereby produce a single thickness after-welt 50 which is heavier than the non-reinforced leg

fabric to the extent of the added welt yarn. This after-welt portion 14, being of single thickness fabric as compared with the double thickness fabric of the top welt 13, is thus of a weight per unit of area which is intermediate that of the leg fabric 11 and the top welt 13 and so improves the balance and insures a better appearing relation between these parts of the stocking. In the stockings as ordinarily produced, there is a sharp contrast in appearance between the fabric forming welt and the leg proper of the stocking, whereas in the stocking of the present invention, this distracting contrast is avoided by continuing the welt yarn a substantial distance beyond the line 15 which demarcates the lower edge of the doubled welt, the body yarn of the leg being interknitted with said welt yarn through as many courses as may be desired to form the after-welt 14.

The knitted construction of the after-welt is probably shown most clearly in Figure 3 wherein it will be observed that the welt yarn 16, which is exclusively employed to knit the fabric of the doubled top welt 13, continues throughout the knitted courses of the after-welt portion 14, while the body yarn 17, which is exclusively employed to knit the stocking leg 11, is employed conjointly with the welt yarn 16 to knit said after-welt 14. The welt yarn 16 and the leg yarn 17 are thus coextensive throughout the area of the after-welt, these two yarns being conjointly employed, by the simultaneous operation of their respective yarn carriers, to form the knitted courses of the after-welt.

While it is preferred to employ a welt yarn having a denier of 75 and a leg yarn having a denier of 50 to thereby produce an after-welt

having a combined yarn denier of 125, it will be understood, of course, that the denier ratio of the welt and leg yarns may be varied as desired without departing from the present invention, and also that the number of courses comprising the after-welt may be varied within wide limits. Accordingly, it is intended to claim the invention broadly, as well as specifically, as indicated by the appended claims.

10 What is claimed as new and useful is:

1. In a stocking having a doubled top welt knitted of yarn of a given denier and a non-reinforced leg portion knitted of yarn of a denier materially less than said given denier, a reinforced after-welt portion extending below said top welt and interknitted with said leg portion, said after-welt portion being knitted throughout of the two yarns respectively forming said top welt and said leg portion of the stocking, the yarn of the top welt being continued into the knitted body of the leg portion of the stocking to reinforce the body yarn of said leg portion throughout all of the courses forming said after-welt.

2. In a stocking having a doubled top welt and a leg portion respectively knitted of yarns of substantially different deniers, a reinforced after-welt portion knitted throughout conjointly of the said welt and leg portion yarns to provide it with a composite denier equal to the sum of the deniers of the said two yarns, said after-welt portion being knitted of a sufficient number of courses to provide a reinforced zone or panel disposed between the doubled top welt and the non-reinforced leg portion of the stocking adequate for gartering purposes.

JOSEPH LARGMAN.
